(57) **CLAIM**

The ornamental design for a braided entry cable, as shown and described.

DESCRIPTION

FIG. 1 is a right perspective view of the braided entry cable showing our new design;

FIG. 2 is a left perspective view of the braided entry cable of FIG. 1;

FIG. 3 is a left elevation view of the braided entry cable of FIG. 1;

FIG. 4 is a right elevation view of the braided entry cable of FIG. 1;

FIG. 5 is a front elevation view of the braided entry cable of FIG. 1; and,

FIG. 6 is a top perspective view of the braided entry cable of FIG. 1.

In FIGS. 1-6, broken lines indicate environmental structure that forms no part of the claimed design.

1 Claim, 6 Drawing Sheets
